ATTORNEY

UNITED STATES PATENT OFFICE.

EDWIN M. WHEELOCK, OF WINONA, MINNESOTA.

DESIGN FOR A TRACTION-WHEEL.

42,264.

Specification for Design. Patented Mar. 5, 1912.

Application filed June 9, 1911. Serial No. 632,251. Term of patent 7 years.

To all whom it may concern:

Be it known that I, EDWIN M. WHEELOCK, a citizen of the United States, residing at Winona, in the county of Winona and State of Minnesota, have invented a new, original, and ornamental Design for a Traction-Wheel, of which the following is a specification, reference being had to the accompanying drawing, forming part thereof.

The figure is a perspective view of a trac-

tion wheel embodying and illustrating my ornamental design.

I claim:

The ornamental design for a traction wheel, as shown.

EDWIN M. WHEELOCK.
